AUTOMATIC INDICATING TARGET

Filed Nov 25, 1930

Fig. 1

UNITED STATES PATENT OFFICE

EMIL BERGFELD, OF OBERHAUSEN, GERMANY

AUTOMATIC INDICATING TARGET

Application filed November 25, 1930, Serial No. 498,010, and in Germany November 25, 1929.

Automatic indicating targets are known, in which the projectile, either piercing the target or striking and repelled thereby, closes certain electric circuits indicating the position of the hit.

The invention differs advantageously from these known arrangements in that the bullet remains adhering to the target and closes hit indicating circuits, known per se, until the bullet is ejected from the disc by a special mechanism operated from the firing point. This is effected in that the disc consists of two plates, the front plate being provided with perforations and adapted to be flapped down by a mechanical pull device and the rear plate being provided with rigid projecting pins corresponding in number to the number of holes in the front plate and registering with these holes in such a manner that the pins engage in the holes of the front plate and leave a certain clearance so that the bullet in striking the target remains in this clearance. If the front plate is flapped down, the bullet is pulled off the pins and ejected, a counterweight returning the flapped down disc into its initial position on the pulling element being released.

An embodiment of the invention is illustrated by way of example in the accompanying drawings, in which:

Fig. 1 shows the target in front elevation.
Fig. 2 is a central vertical cross section of Fig. 1.

Fig. 3 shows the number box with connecting wires.

The target consists substantially of a steel disc *a*, in which the individual rings are formed by bores *b* and contact pins *d* of a rear wooden plate *c*, said contact pins *d* engaging each with a clearance in the bores *b* of the steel disc *a*, are fixed in such a manner that the pins of each ring are electrically connected together by contact rings *e*, which are individually insulated the ones against the others, the pins *d* in the bores *b* slightly receding behind the front surface of the disc *a*. The rings *d* are connected by means of wires 1 to 12 to the individual sources of light *f* of the corresponding number compartments of an indicating box *g*, a common return wire passing

from the individual sources of light to the source of current *h*, whereas the supply wire extends from the source of current *h* to the steel disc *a*. A lead bullet *i*, which for example has entered a bore *b* of the ring 7, connects the steel disc *a* to the contact ring *e* through the pin *d* situated therein so that the source of light of the compartment 7 illuminates the number 7 in the indicating box. If the lead bullet connects two bores of two neighbouring rings, the corresponding numbers of both rings will be illuminated. By means of the adhering bullet the marksman can see on the disc, where his bullet has hit. The contact pin *d*, situated in the bull's-eye, is made hollow, and a space *k* is provided behind this pin and separately illuminated so that the bull's-eye of the target is indirectly illuminated for facilitating the taking of aim. This source of light can be controlled by a separate switch not shown in the drawings. For ejecting the adhering bullet, the steel disc *a* is hingedly mounted on pins *m* so that by pulling the elbow lever *n* in the direction of the arrow *A*, the disc *a* can be swung away from the contact pins to a stop *o*, so that the bullet *i* is removed from the contact pins by shifting the disc *a* and drops out of the disc *a* when this disc strikes the stop *o*. On the elbow lever *n* being released, the steel disc *a* is returned into its initial position by a counterweight *p*.

In order to afford the contact pins *d*, a better hold in the wooden plate *c* and to impart a smooth bearing surface to the steel disc *a*, a plate *q* is arranged between the disc *a* and the wooden plate *c*, and fixed to this latter, which plate *q* may be made of hard insulating material.

I claim:

1. An automatic indicating target, in which certain electric circuits are closed by the bullet striking the target, comprising in combination means for retaining the bullet in the target and temporarily closing the corresponding circuit, and mechanical means for ejecting the bullet from the target adapted to be actuated from the firing position.

2. A target as specified in claim 1, comprising a disc made of sheet steel having rings

- composed of closely juxtaposed bores, a plate arranged behind said steel disc, contact pins on said plate adapted to engage with play in the bores of said steel disc, mutually insulated contact rings connecting the pins of the individual rings in said steel disc, and electric circuits one for each of said rings adapted to be closed when a bullet strikes one of said contact pins.
- 10 3. A target as specified in claim 1, comprising in combination a steel disc having rings formed by bores, a plate arranged behind said steel disc, contact pins on said plate engaging with play in the bores of said disc, a hinge pin carrying said steel disc, an elbow lever adapted to swing said disc on said hinge pin, a pull element adapted to actuate said elbow lever, a stop adapted to arrest the movement of said steel disc, and a counterweight adapted to return said disc to its initial position on said pull element being released.
